CARL OSCAR ANDERSON, OF SPRINGFIELD, ILLINOIS, ASSIGNOR, BY MESNE ASSIGNMENTS, TO THORNE BROTHERS, INCORPORATED, OF CHICAGO, ILLINOIS, A CORPORATION OF ILLINOIS.

LUBRICATING-BEARING.

1,369,211.

Specification of Letters Patent. Patented Feb. 22, 1921.

Application filed November 2, 1917. Serial No. 199,872.

To all whom it may concern:

Be it known that I, CARL OSCAR ANDERSON, a citizen of the United States, residing at Springfield, in the county of Sangamon and State of Illinois, have invented certain new and useful Improvements in Lubricating-Bearings, of which the following is a specification.

The present invention relates to liquid separating machines, such as centrifugal cream separators, and is more particularly concerned with means for the lubrication of the spindle by which the separator bowl is supported and operated.

15 The object of the invention is to provide a novel form of bearing for the spindle which may be inexpensively produced, and which will embody simple and reliable means for feeding an abundant supply of oil to the 20 spindle to insure free running thereof. These spindles operate at high speed. Their general tendency, induced by such high speed, is to throw off the oil, so that difficulty is experienced in supplying a sufficient quantity of the oil to afford adequate 25 lubrication. By the construction of the herein-described bearing these objections are obviated and the spindle is always provided with the requisite quantity of lubricant.

30 The invention also seeks to provide a lubricating bearing wherein provision is made for positive feeding of the lubricant throughout the entire length of the bearing thereby eliminating heating of the bearing by reason of failure of the oil to reach all parts 35 thereof.

With these general objects in view, and others which will appear as the nature of the improvements is better understood, the invention consists substantially in the novel construction, combination and arrangement of parts hereinafter fully described, illustrated in the accompanying drawings, and finally pointed out in the appended claims.

45 In the drawings—

Figure 1 is a vertical transverse sectional view of a cream separator equipped with the herein-described invention, only those parts of the apparatus being illustrated as 50 sufficient for an intelligent understanding of the invention;

Fig. 2 is a vertical transverse sectional view, on an enlarged scale, of the preferred form of the bearing;

Fig. 3 is a top plan view thereof; 55

Fig. 4 is a horizontal sectional view on the line 4—4, of Fig. 2;

Figs. 5 and 6 are vertical transverse sectional views of modified forms of the bearing. 60

Referring now in detail to the accompanying drawings, the numeral 10 designates the frame proper of the machine having associated therewith the usual bearing body or casing 11 in which is disposed the usual 65 separating bowl (not shown). Also associated with the frame 10 is the worm wheel 12 actuated from the crank shaft 13, said wheel being inclosed in said frame and working within an oil cavity 14 at the interior of said frame. The numeral 15 designates the usual worm spindle which supports and operates at its upper end the separating bowl, before referred to; 16 designates the stop screw for the spindle 15; 17 70 is the upper bearing for the spindle 15, and 18 designates the springs for holding the bearing 17 in place in the opening formed at the lower end of the casing 11. The parts enumerated are of common construction, 75 preferably those found in the Sattley separator of commerce, with the exception of the construction of the bearing 17. This forms the subject of and includes the present invention. 80

As before stated, difficulty has been experienced heretofore in the proper lubrication of the spindle 15 within the bearing 17, the tendency being for the oil to be thrown off during the high speed rotation of the 90 spindle. To prevent this the present invention contemplates such a construction of the bearing 17 as to provide an abundant supply of oil for the bore thereof and the spindle working within the bore, and to maintain a 95 proper flow of the oil to the bearing while the spindle is in operation. To this end it is proposed to equip the bearing with an oil reservoir at its lower end which will be continuously supplied with oil from the 100 cavity 14 during the operation of the worm wheel 12, and also to provide means in connection with the oil reservoir, whereby to establish a positive feed of the oil from the reservoir to the bore of the bearing and the 105 spindle operating within said bore. Several forms of construction by which the object of the invention may be attained are dis-

closed, but that illustrated in Fig. 2 is regarded as the preferred form. Referring, therefore, to Fig. 2 it will be observed that the bearing includes an elongated sleeve 19 having a cylindrical bore 20 extending lengthwise thereof, the upper end of said sleeve terminating in a cup-shaped flange 21 in which is formed a discharge opening 22, the purpose of which will presently appear.

At the lower end of the sleeve 19 is formed a horizontal receiving flange 23, and at the lower extremity of said sleeve 19 is an annular rib 24 which surrounds the lower end of the bore 20 and provides at such end a cavity 25, the diameter of which is greater than the diameter of the bore 20. The cavity 25 provides an oil pocket or reservoir which is fed by a plurality of inclined openings or passages 26 extending from the junction point of the flange 23 with the sleeve 19 into said cavity 25, said passages 26 being also disposed in radial relation to the bore 20, as clearly illustrated in Fig. 4. When, therefore, oil is deposited on the receiving flange 23 it enters the passages 26, and by reason of the inclination of said passages the oil will gravitate into the cavity or pocket 25. The exterior of the rib 24 is grooved to provide a bead 27, and mounted on said rib 24 is a closure cap 28 having a central perforation or opening 29 for the reception of the worm spindle 15 when the bearing is assembled thereon. The diameter of the opening 29 is the same as the diameter of the bore 20 of the sleeve 19; hence, when the bearing is associated with the worm spindle 15 the latter fills the bore 20 and the opening 29 so that the pocket or cavity 25 is closed against the exit of the oil through said opening 29. By reason of the bead 27 formed on the rib 24 the edges of the closure cap 28 may be crimped into the annular groove by which said bead is formed, thereby effectually holding the closure cap on the rib 24.

It has been stated that one of the objects of the invention is to provide means for positively feeding the oil into the bore 20 and through the latter so that the portion of the spindle 15 working therein will be properly lubricated. This is effected by an inclined deflector 30 which extends transversely from the rib 24 to a point coextensive with the edge of the bore 20, and likewise extends longitudinally from the end of the sleeve 19 to the lower edge of the rib 24. The deflector 30 constitutes a diaphragm or partition within the pocket 25, and when the bearing is assembled on the worm spindle 15 the inner edge of the deflector 30 is adjacent to said spindle. The rotary flow of the oil, therefore, in the pocket 25, induced by the rotation of the spindle 15, is interrupted by the deflector 30, and the oil is thus turned inwardly against the spindle,

the deflector 30 serving to create a pressure by reason of the forcing of the oil thereagainst under the rotation of said spindle. Consequently, with the oil thus obstructed in its rotary flow it is directed against the spindle and this pressure causes the oil to rise along the spindle within the bore 20 and to flow upwardly through the sleeve 19 to the upper end thereof. To assist in this flow the bore 20 may be provided with a spiral groove 31, but this is not essential, and may be dispensed with if desired. As the oil is discharged at the upper end of the sleeve 19 it is received by the cup-shaped flange 21 and when a sufficient quantity has been gathered by said flange it will flow downwardly through the discharge opening 22 and be received by the cavity 14.

To preclude any oil that may accumulate in the cup-shaped flange 21 being thrown outwardly therefrom by the rotation of the spindle 15 a perforated cover 31^a may be placed over said flange, said cover surrounding the spindle 15, as illustrated in Fig. 1. This will confine the oil to the flange 21 and its only point of exit will be through the discharge opening 22. With the parts assembled as illustrated in Fig. 1, a sufficient quantity of oil is placed within the cavity 14 of the frame 10 so that its upper level will be at approximately the point indicated by the dotted line in Fig. 1. The surface of the oil is therefore slightly above the lower edge of the worm wheel 12. As the wheel 12 is rotated the oil is gathered thereby, carried to the upper portion of the cavity 14 and splashed by the wheel onto the bearing 19. As the oil is caught by the receiving flange 23 it passes into the openings 26, and the latter convey the oil to the pocket 25. By reason of the fact that these passages 26 are radially disposed and are inclined with respect to the pocket 25, the oil freely gravitates therethrough into said pocket. When a sufficient quantity of the oil has accumulated within the pocket the rotation of the spindle 15 will cause the oil to contact the deflector 30 which will direct the oil against the spindle, in the manner above described, whence the oil will rise along the spindle and travel through the bore 20 of the bearing 19 to the upper end of the latter. This movement of the oil continues throughout the rotation of the spindle 15, and as it is forced outwardly through the upper end of the bore it accumulates on the cup-shaped flange 21 and is again returned to the cavity 14 where it is repeatedly splashed by the operation of the worm wheel 12 onto the bearing 19 in the manner described. It will thus be seen that an abundant supply of oil is constantly provided for the bearing, and the positive feed of the oil through the bearing is effected by the means hereinbefore described.

In Fig. 5 is illustrated another form of the invention. In this form the construction of the sleeve 19, with its flanges 21 and 23, is the same as illustrated in Fig. 2. The oil pocket or reservoir, however, is different. The changed form includes a cap 32 having an attaching flange 33 which is secured by suitable means, such as rivets or screws, to the flange 23. The cap 32 has a central 10 perforation 34 to receive the worm spindle 15, and is likewise provided with an inclined deflector 35. In this instance the deflector 35 is formed integral with the cap 32 and extends up to the lower edge of the 15 sleeve 19.

The arrangement illustrated in Fig. 5 shows the adaptation of the invention to bearings not particularly constructed for lubricating purposes.

20 Fig. 6 illustrates a further form of the invention wherein the same is included as an integral part of the construction of the sleeve 19. In this form the lower end of the sleeve 19 is provided with a head 36 25 provided at its interior with an annular groove 37 formed by an enlargement of the bore 20, said groove 37 providing the cavity for the oil. Within the groove 37 is an inclined deflector 38 performing the same 30 functions as the deflectors 30 and 35 of the forms shown in Figs. 2 and 5. The head 36 is likewise formed with an opening 39 for receiving the spindle 15.

Obviously, the action of the oil in being 35 fed to and as it flows through the constructions illustrated in Figs. 5 and 6 is the same as in the other forms of the invention.

I claim:

1. A bearing of the class described, comprising a body provided with a bore adapted 40 to receive the shaft to be lubricated, a lubricant reservoir associated with said body, and means arranged transversely of said reservoir and extending into coöperative relation with the shaft for effecting 45 positive feed of the lubricant through the bore of the body during rotation of the shaft.

2. A bearing of the class described, comprising a body provided with a bore adapted 50 to receive the shaft to be lubricated, a reservoir for the lubricant arranged at one end of said body, and means within said reservoir adapted to coöperate with the 55 shaft for effecting positive feed of the lubricant through the bore of the body during rotation of the shaft.

3. A bearing of the class described, comprising a body provided with a bore adapted 60 to receive the shaft to be lubricated, a reservoir for the lubricant arranged at one end of said body, and a deflector arranged within said reservoir and adapted to coöperate with the shaft to direct the lubricant upon the 65 shaft when the latter is rotated.

4. A bearing of the class described, comprising a body provided with a bore adapted 70 to receive the shaft to be lubricated, a reservoir for the lubricant arranged at one end of said body, and an angularly disposed deflector arranged within said reservoir and adapted to coöperate with the shaft for directing the lubricant upon the shaft during rotation of the latter.

5. A bearing of the class described, comprising a body provided with a bore adapted 75 to receive the shaft to be lubricated, a reservoir for the lubricant arranged at one end of said body and of greater diameter than the diameter of said bore, and a deflector arranged across said reservoir and adapted to coöperate with the shaft for directing the lubricant to the surface of the shaft during rotation of the latter.

6. A bearing of the class described, comprising a body provided with a bore adapted 80 to receive the shaft to be lubricated, a reservoir for the lubricant arranged at one end of said body, and a deflector arranged within said reservoir and disposed at an angle to 85 the axis of the bearing for directing the lubricant to the shaft during rotation of the latter.

7. A bearing of the class described, comprising an elongated sleeve the bore of 90 which is adapted to receive the shaft to be lubricated, a reservoir at one end of said sleeve adapted to receive the lubricant, said sleeve being provided with a plurality of radially disposed openings in communication 95 with said reservoir for feeding the lubricant to the latter, and means within the reservoir for effecting positive feed of the lubricant through the bore of said sleeve during rotation of the shaft.

8. A bearing of the class described, comprising an elongated sleeve the bore of 100 which is adapted to receive the shaft to be lubricated, a reservoir for the lubricant arranged at one end of said sleeve, a receiving 110 flange carried by said sleeve for collecting lubricant deposited upon the sleeve, said sleeve being provided with a plurality of passages affording communication between the surface of said receiving flange and the 115 interior of said reservoir, and means within the reservoir for effecting positive feed of the lubricant through the bore of the sleeve during rotation of said shaft.

9. A bearing of the class described, comprising an elongated sleeve the bore of 120 which is adapted to receive the shaft to be lubricated, a reservoir for the lubricant arranged at one end of said body, a receiving flange carried by said sleeve and adapted to 125 collect the lubricant deposited upon said sleeve, said sleeve being provided with a plurality of passages affording communication between the surface of said receiving flange and the interior of said reservoir, and 130

- an inclined deflector arranged within said reservoir and adapted to coöperate with the shaft for effecting positive feed of the lubricant through the bore of the sleeve during 5 rotation of said shaft.
10. A bearing of the class described, comprising an elongated sleeve the bore of which is adapted to receive the shaft to be lubricated, a reservoir for the lubricant arranged at one end of said body, a receiving flange carried by said sleeve and adapted to collect the lubricant deposited upon said sleeve, said sleeve being provided with a plurality of passages affording communication 15 between the surface of said receiving flange and the interior of said reservoir, means within the reservoir adapted to coöperate with the shaft for effecting positive feed of the lubricant through the bore of the sleeve 20 during rotation of said shaft, and a collecting flange carried by said sleeve for receiving the lubricant discharged from said sleeve, said collecting flange having means for discharging the lubricant collected 25 thereby.
11. In a centrifugal machine, the combination with the bowl-actuating spindle, and its operating gear, of a bearing for said spindle having a bore for receiving the latter, a lubricant reservoir associated with said bearing and surrounding the spindle, and means 30 within said reservoir adapted to coöperate with said spindle for effecting positive feeding of the lubricant to the bearing during 35 rotation of said spindle.
12. In a centrifugal machine, the combination with the bowl-actuating spindle, and its operating gear, of a bearing for said spindle having a bore for receiving the latter, a lubricant reservoir associated with said bearing and surrounding the spindle, and a deflector arranged within said reservoir for 40 directing the lubricant against the spindle and feeding it through the bearing during 45 rotation of said spindle.
13. In a centrifugal machine, the combination with the bowl-actuating spindle, and its operating gear, of a bearing for said spindle having a bore for receiving the latter, a lubricant reservoir associated with 50 said bearing and surrounding the spindle, and a deflector arranged within said reservoir and inclined at an angle to the axis of the spindle, said deflector being adapted to coöperate with said spindle to direct the lubricant against the spindle for feeding it through the bearing during rotation of said spindle.
14. In a centrifugal machine, the combination with the bowl-actuating spindle, and its operating gear, of a bearing for said spindle having a bore for receiving the latter, a lubricant reservoir arranged at one end of said bearing and surrounding the spindle, a receiving flange also carried by 55 said bearing, said receiving flange being arranged adjacent to said reservoir and adapted to collect lubricant deposited on said sleeve, the latter being also provided with a plurality of apertures affording communication 60 between the surface of said receiving flange and said reservoir for feeding the lubricant to said reservoir, means within the reservoir adapted to coöperate with said spindle to effect a positive feed of the lubricant through the bore of the bearing during 65 rotation of said spindle, and a collecting flange also carried by said sleeve for receiving the lubricant discharged from the bore of the sleeve, said collecting flange being 70 provided with means for discharging the lubricant collected thereby.
- 75 In testimony whereof I have hereunto signed my name in the presence of two subscribing witnesses.

CARL OSCAR ANDERSON.
